UNITED STATES PATENT OFFICE.

CHARLES HERBERT VAIL, OF GLOVERSVILLE, NEW YORK, ASSIGNOR TO ANTHONY-VAIL TOOL & MACHINE COMPANY, OF GLOVERSVILLE, NEW YORK.

DRYING FORMER AND SOCKET MEMBER THEREFOR.

Application filed June 10, 1922. Serial No. 567,394.

To all whom it may concern:

Be it known that I, CHARLES HERBERT VAIL, a citizen of the United States of America, residing at Gloversville, in the county of Fulton and State of New York, have invented certain new and useful Improvements in Drying Formers and Socket Members Therefor, of which the following is a specification.

This invention relates to certain new and useful improvements in drying formers and socket members therefor and has particular reference to the general improvement of steam drying forms of the type generally employed for the drying and forming or finishing of gloves.

The principal object of the invention is to provide a steam drying form including a socket and a drying board carried thereby, cooperatively constructed for returning the water of condensation, which takes place in the board and socket, to the boiler or source of supply through the main steam pipe without additional piping.

In the specific application of the invention to glove finishing forms, the device embodies a socket to which is attached a hand-like form which is hollow and shaped like a person's hand with fingers but no thumb. The steam enters the hand and then passes up to the fingers through the socket, and as it condenses the water formed thereby returns down the hand to the socket thence back to the boiler through the main steam supply pipe.

In so far as I am aware, sockets of this kind have all heretofore been constructed so that the steam, when it condensed, would form water in the hand and fingers, thus causing the latter to become cool. A certain amount of heat is necessary to "lay off" leather gloves. Heretofore, when the hand became cold by reason of condensation of steam forming in the hand, it was necessary to stop operating and draw off the water and then again introduce live steam into the hand. The present invention provides a socket and drying board which are cooperatively constructed to permit the live steam to continue to flow through and into the hand, and as the steam condenses to allow the water formed thereby to flow down the hand through the socket and then back to the main steam supply pipe to the boiler.

Another object of the invention is to pro-

vide a socket for steam drying forms embodying a control arrangement for simultaneously introducing steam into the form and permitting escape of the same to the atmosphere for removing air from the interior of the form, which means is further operable at will to close the atmospheric vent and simultaneously maintain the steam supply to the form and open communication between the steam supply and the interior of the form for the return of condensation to the source of steam supply through the main steam supply pipe.

With the above general and specific objects in view, the invention consists in the novel form, combination, and arrangement of parts hereinafter more fully described, shown in the accompanying drawings and claimed.

In the drawings forming a part of this application and in which like designating characters refer to corresponding parts throughout the several views:

Fig. 1 is a view partly broken away and in side elevation, of a steam drying form constructed in accordance with the present invention.

Fig. 2 is a view partly broken away and in longitudinal section on line II—II of Fig. 1, of the device shown in the latter figure.

Fig. 3 is a fragmentary sectional view on line III—III of Fig. 2.

Fig. 4 is a side elevational view of the valve plug.

Fig. 5 is an end view of the device shown in Fig. 4 looking toward the left of the latter.

Fig. 6 is a side elevational view of the branch steam pipe supporting plug, and

Fig. 7 is a top plan view of the device shown in Fig. 6.

Referring more in detail to the several views, the present invention embodies a socket 5 having a control valve 6 and supporting a drying form 7 which is herein illustrated in the form ordinarily employed for the shaping of leather gloves and which embodies the usual palm portion with four finger members 7', the socket 5 and the drying form being of hollow construction.

In accordance with the present invention, the socket 5 is adapted to be suitably fastened to a table of like support in an up-

right position, and this socket embodies a threaded lower end portion 8 adapted to be suitably connected to a steam supply pipe, not shown. The upper end of the 5 socket member 5 is enlarged and internally threaded as at 9 and is provided with a smooth restricted bore just below this threaded portion as at 10 for snug slidable reception of the stem 11 of the form member 7 a packing gland or bushing 12 being externally threaded and screwed into the threaded portion 9 with a packing 13 interposed between the inner or lower end of the bushing 12 and the shoulder 14 of 10 the socket member 5 so that a steam-tight joint is had between the stem 11 and the socket member when the bushing 12 is threaded into said socket member. It will be understood the loosening of the bushing 20 12 will allow ready removal of the form 7 by reason of the stem 11 slidably fitting in said bushing also, and in this way the forms may be expeditiously removed for the insertion of different kinds of forms whenever 25 found desirable.

A plug 15 is suitably secured in the lower end of the stem 11 and has a reduced upper end portion 16 which is provided with a series of openings 17 in which branch 30 steam pipes 18 are suitably secured, one pipe 18 being provided for and extending upwardly into each of the finger members 7', and the lower ends of said steam pipes 18 are all communicating with a relatively 35 large axial boss provided in the remaining portion of the plug 15. The socket member 5 is provided, near the threaded end 8, with a partition 19 having a threaded bore centrally thereof into which is screwed a relatively 40 small steam conducting tube 20 whose upper end removably fits the large bore of the plug 15. Journaled transversely of the partition 19 is the tapered rotary plug valve member 6 having an operating 45 handle 22 and provided with a plurality of ports 23, 24, and 25, the ports 24 and 23 being parallel with each other and the ports 25 being at an angle to said ports 23 and 24 for a purpose which will presently 50 become apparent.

The inner end of the tube 20 communicates with a segmental-shaped chamber 26 provided in the partition 19, which chamber extends from the inner end of the tube 20 55 laterally toward one side of the socket member and this chamber 26 is in alinement with the port 23 of the valve member 6, which port also communicates with the bore of the threaded portion 8. The partition 19 60 is also provided with a port 27 adapted to be alined with the port 24 of the valve member 6 and the port 28 adapted to be alined with the port 25 of said valve member 6, the port 28 being extended laterally 65 below the valve member 6 as at 29 for com-

munication with the atmosphere or with a suitable vent valve of an automatic type. The handle 22 may be provided with an inwardly projecting pin 30 and the body of the socket member 5 at this point may have 70 a flat surface of enlarged form provided with an external arcuate groove 31 in which said pin rides for limiting the turning movement of the valve member 6, the handle being shown in Fig. 1 in a position wherein 75 the ports 23 and 24 are opened and the port 25 closed. The groove 31 is provided with a graduation or mark 32 for indicating the proper position of the handle 22 when the port 25 is open, and the port 23 communicates with the tube 20 by reason of the provision of chamber 26, while the port 24 is closed. When the handle is at the opposite end of the groove 31 or extends parallel 80 with the longitudinal axis of the socket 5 the ports 23, 24 and 25 will all be closed. In order to provide communication between the interior of the form 7 and the ports 27 and 28, the plug 15 is provided with a plurality of longitudinally extending peripheral grooves 33 which will allow the escape of air from the form 7 to the atmosphere when the port 23 is opened together with the port 25 while the port 24 is closed, or to allow the return of condensation from the interior of the form 7 to the inlet end of the socket 5 when ports 23 and 24 are opened and port 25 is closed. 90

In operation, the drying form 7 is operatively connected to the socket 5, and the article to be dried is placed upon the form 7. The valve handle 22 is then turned to register pin 30 with the graduation 32, at which time the steam will readily flow from the supply pipe through the port 23 into chamber 26 and thence into tube 20 and tubes 18. The port 24 will be out of alinement with the port 27 or, in other words, port 24 will be closed while port 25 will be open. The steam will escape through the upper end of the tubes 18 and force the air which may be trapped within the interior of the form 7 downwardly through the grooves 33 and port 28 to the atmosphere. 110 As soon as steam begins to flow through the port 28 to the atmosphere the handle is turned to the full line position of Fig. 1 so as to close the port 25 and open the port 24 while still maintaining the port 23 but moving said port 23 to a position wherein 115 the same is longitudinally alined with the tube 20 as seen in Fig. 3. The form 7 is then quickly heated and as the steam condenses within the form 7 it will pass downwardly along the inner surfaces of the form 7 and through the groove 33 to the port 27 from whence it may pass through the port 24 and return through the main steam supply pipe to the source of steam supply for again being converted into steam. The con- 120 125 130

densation will readily pass in this manner opposite to the direction of movement of the steam and the fact that separate return piping for the water of condensation has been 5 found entirely unnecessary as long as separate paths for the flow of the steam and condensation is provided in the socket and form for initially establishing a well defined circuit or passage for the steam and 10 condensation.

While the form of the invention herein shown and described is what is believed to be the preferred embodiment thereof, it is nevertheless to be understood that various 15 forms, modifications and arrangements of the parts may be made without departing from the spirit and scope of the invention as claimed.

What I claim as new is:—

20 1. In a steam drying device, a form board, a supporting socket therefor having a single inlet bore, means to conduct the steam from said inlet bore to the upper or outer end of the form board interiorly of the latter, means to provide a separate passage for the return of condensation from the interior of the form board to said inlet bore and a single valve for the steam supply and condensation return.

30 2. In a steam drying device, a form board, a supporting socket therefor having a single inlet bore, means to conduct the steam from said inlet bore to the upper or outer end of the form board interiorly of the latter, 35 means to provide a separate passage for the return of condensation from the interior of the form board to said inlet bore, said socket having a vent to the atmosphere in communication with the path for the return 40 of condensation, and a single valve to simultaneously establish communication between the inlet bore and the steam conducting means of the form board and communication between the condensation return and the atmosphere.

45 3. In a steam drying device, a form board, a supporting socket therefor having a single inlet bore, means to conduct the steam from said inlet bore to the upper or outer end of the form board interiorly of the latter, means to provide a separate passage for the return of condensation from the interior of the form board to said inlet bore, said socket having a vent to the atmosphere in 50 communication with the path for the return of condensation, a single valve to simultaneously establish communication between the inlet bore and the steam conducting means of the form board and communication between the condensation return and the atmosphere, said last named means being further simultaneously operable for cutting off the vent to the atmosphere while establishing communication between the condensation return and the inlet bore and maintain- 55

ing communication between the inlet bore and the steam conducting means.

4. In a steam drying device, a form board, a supporting socket therefor having a single inlet bore, means to conduct the steam from 70 said inlet bore to the upper or outer end of the form board interiorly of the latter, means to provide a separate passage for the return of condensation from the interior of the form board to said inlet bore, said socket 75 having a vent to the atmosphere in communication with the path for the return of condensation, and a single valve to simultaneously establish communication between the inlet bore and the steam conducting means 80 of the form board and communication between the condensation return and the atmosphere, said last named means being further simultaneously operable for cutting off the vent to the atmosphere while establishing 85 communication between the condensation return and the inlet bore and maintaining communication between the inlet bore and the steam conducting means, said valve being of the rotary type and having three 90 ports, and the socket having a partition with registering ports cooperating with the port of the valve member.

5. In a steam drying device, the combination of a hand board having a tubular stem or shank, a socket for snugly receiving this shank, means to removably secure the shank in the socket with a steam-tight fit, a plug secured within the shank and having a plurality of longitudinal peripheral grooves, 100 tubes leading from the high points of the board to and carried by the plug, said socket having a transverse partition formed with three longitudinally extending ports two of which communicate at the lower end of the 105 socket and the remaining one of which extends to the atmosphere, a tube connecting one port of the partition with the tubes of the board, and a single supporting valve to simultaneously open the atmospheric port and the port communicating with the tubes while closing the remaining port and for cutting off the path of condensation return and the atmosphere while establishing communication 110 between the tubes and the inlet bore of the socket and communication between the condensation return and said inlet bore of the socket.

6. In combination with a steam drying form having a tubular stem, a socket removably receiving said stem, a plug secured in said stem and supporting a plurality of steam supply tubes terminating at the high points of the form, said socket having separate longitudinal ports below said plug both communicating with the single inlet bore of the socket, a tube connecting one of the socket ports with the plug and having its upper end removably fitted in said plug whereby the form may be readily detached 125 130

from the socket, and means establishing communication between the other port and the interior of the form past said plug.

7. In combination with a steam drying form having a tubular stem, a socket removably receiving said stem, a plug secured in said stem and supporting a plurality of steam supply tubes terminating at the high points of the form, said socket having separate longitudinal ports below said plug both communicating with the single inlet bore of the socket, a tube connecting one of the socket ports with the plug and having its upper end removably fitted in said plug whereby the form may be readily detached from the socket, means establishing communication between the other port and the interior of the form past said plug, said socket having a further port communicating with the atmosphere, and a valve operable to close all of the ports of the socket, to close the port to the atmosphere while providing communication through the other two ports, and to close communication through the port

leading from the interior of the socket and 25 form to the inlet bore of the socket while establishing communication through the port leading to the tube and the port leading to the atmosphere.

8. In a steam drying device, a drying 30 form, a supporting socket therefor, a steam supply, condensation return and air vent associated with the socket, and a single controlling valve therefor.

9. In a steam drying device, a drying 35 form, a supporting socket therefor, a steam supply, condensation return and air vent associated with the socket, and a single three-ported controlling valve therefor.

10. In a steam drying device, a drying 40 form, a supporting socket therefor, a steam supply, condensation return and air vent associated with the socket, and a single valve for rendering the steam supply and condensation return operative and shutting off the 45 air vent.

In testimony whereof I affix my signature.
C. HERBERT VAIL.
